BAG STAPLING MACHINE

Webster Noyes Baker, Baldwin, Ross C. Hurley,
Great Kills, and Robert N. Cundall, Lacka-
wanna, N. Y., assignors to Bagpak, Inc., a cor-
poration of Delaware

Application November 15, 1934, Serial No. 753,119

11 Claims. (Cl. 93—8)

Our invention comprises a device for applying gusset holding means to the corners of an open mouth gusseted bag, such holding means being described and claimed in the copending application of Webster Noyes Baker, Harry C. Knodle and J. Walker Grimm, filed concurrently herewith, Serial No. 753,118, filed November 15, 1934, entitled Bags, now Patent No. 2,017,838, dated October 22, 1935.

The object of our invention is to devise means to form and apply strips of reinforcing material around the side edges of each corner of a bag and to drive fastening means through the reinforcing strip and the bag, the machine being adjustable to accommodate various sizes of bags. An advantage of our invention lies in the simplicity of construction and its universal adaptability.

Other and further objects and advantages of our invention will be apparent from the following description taken in connection with the accompanying drawings, wherein like numerals refer to like parts throughout:

Fig. 1 is a plan view of the machine as a whole;
Fig. 2 is a front elevation of the machine;

Fig. 3 is a partial detail view of the strip feeding mechanism;

Fig. 4 is a partial section of Fig. 5, taken along line 4—4;

Fig. 5 is a partial section of Fig. 1, taken along line 5—5;

Figs. 6, 7 and 8 are views similar to Fig. 5 showing successive stages of the operation of the machine; and

Fig. 9 is a plan view of a corner of the finished bag.

The machine comprises two stapling heads 20 and 21, driven by a common motor 22. The stapling heads may be of any suitable type, and may insert fastening elements known as "staples", "rivets", "eyelets", etc., but preferably is of the type for inserting and clinching wire staples, as illustrated.

The motor 22 is connected to the stapling heads through enclosed reducing gears 24 and 25 and any well known one revolution clutch 26 controlled by a treadle 27 or other control means. Engagement of clutch 26 turns shaft 28 through one revolution and causes a single cycle of operation. Shaft 28 is the drive shaft of head 20, and drives shaft 29 of head 21 to operate the two heads in unison through sprocket 30 fixed to shaft 28, chain 31, sprockets 32 and 33 fixed to a floating shaft 34, chain 35, and sprocket 36 fixed to shaft 29. Floating shaft 34 is supported by bearings in arm 37, freely mounted on shaft 28,

and in arms 38 and 39, freely mounted on shaft 29, so that the heads may be shifted laterally with respect to one another without affecting the driving means. Head 20 is mounted on a fixed bed 40 while head 21 is mounted on a shifting bed 41 adjusted laterally by means of a screw 42 carried by the frame 43. Associated with head 20 is a bar 44 carrying a plate 45, and with head 21 is a bar 46 carrying a plate 47, the two plates constituting a bag supporting table.

The mechanism for folding a reinforcing strip over the corner of the bag and clinching the staple is as follows:

Shaft 28 drives a shaft 50 through sprocket 51, chain 52 and sprocket 53. Shaft 50 drives a shaft 54 through bevel gears 55 and 56. Shaft 54 drives right and left hand mechanisms, one only of which need be described, the right end of shaft 54 having a long keyway 57 to allow shifting of head 21.

The left hand mechanism comprises a box cam 60 having cam slots 61 and 62. Slot 61 rocks a lever 63 about pivot 64, and slot 62 rocks a lever 65 about its pivot 66. Lever 63 is connected by a pin and slot to a forked bar 70, and lever 65 is similarly connected to a knife 71, bar 70 and knife 71 being slidably guided in bearings on a standard 72.

Mounted upon the plate 45 is a guide 75 extending over the table for a slight distance. The forward edge of the guide is flared to allow ready insertion of the corner of a bag and is so arranged as to compress the plies of the bag slightly and bring the corner thereof into proper relationship with the stapling mechanism. A back guide 76 is mounted upon bar 44 to limit the movement of the bag. Guide 75 is separated from guide 76 and a wide slot is cut into bar 44 at 77 to provide clearance for rod 78, and the reinforcing strip as will presently appear. Slot 77 is extended at 78 to provide a seat for the end of lower fork 79 of rod 78. After a bag has been inserted and the clutch engaged, rod 78 is caused to move into slot 77 with the forks 79 and 80 straddling the edge of the bag as in Fig. 7.

Shaft 54 drives a forwardly extending shaft 85 through bevel gears 86 and 87. At the forward end of shaft 85 is a gear 88 (Fig. 3) driving feed wheels 89 and 90 through gears 91 and 92, respectively. A portion of the peripheries of wheels 89 and 90 are provided with enlargements 93 and 94, respectively, which are preferably strips of rubber or some other frictional material. A continuous strip of reinforcing material 100 is guided between wheels 89 and 90.

from a suitable source of supply. During such times as the enlargements 93 and 94 on the feed wheels engage the strip 100 it will be fed upwardly (Fig. 5) past a knife 101 mounted upon bar 44 and extending across the slot 77. Spring clips 102 and 103 are mounted upon knife 101 and the bearing guide of knife 71, respectively, and are so arranged as to grip the strip 100 with sufficient force to prevent it from dropping when 10 the feed wheels clear the strip (Fig. 6). At the instant that the feed wheels clear the strip, knife 71 is actuated to cut a suitable length from the strip thereby creating the reinforcing strip 121 which is bent around the edge of the bag. 15 At practically the same instant the forward flaring tips of forks 79 and 80 engage the strip and bend it around the edge of the bag as indicated in Figs. 6 and 7, the slot 77 in bar 44 allowing the lower end of the reinforcing strip to be bent 20 upward.

The stapling head 20 is provided with the usual staple and hammer guide 110 which is so timed as to start its downward movement as the upper end of the reinforcing strip is bent around the 25 bag. Fork 80 is provided with a slot 111 to receive the lower end of the staple guide, allowing it to rest upon the upper surface of the reinforcing strip. During this time rod 70 and knife 71 remain stationary while wheels 89 and 90 continue to 30 revolve. In Fig. 8 the staple has been driven, the lower fork 79, which is now supported by the lower side of slot 78, acting as the anvil to clinch the staple. Immediately afterwards rod 70, knife 71 and staple guide 110 are withdrawn to 35 the position of Fig. 5, and feed wheels 89 and 90 come to rest before the enlargements engage the strip 100, to be in readiness for the next operation.

The opposite edge of the bag is treated simultaneously in the same fashion by similar mechanism except that it is a right hand device instead of a left hand device and is movable with the stapling head 21. Fig. 9 shows the corner of a bag A having a staple 120 and a reinforcing strip 121 applied thereto. The opposite corner of the bag is similar with the stapling strip reversed.

Modifications and alterations of our invention will be apparent to persons skilled in the art 50 and we do not intend to be limited to the exact details disclosed in this preferred embodiment. We claim as our invention such modifications and alterations as come within the scope of the following claims, which are to be broadly construed.

55 We claim:

1. In combination; means for positioning a strip of reinforcing material over each corner of an open mouth bag; and means for applying fastening means to retain said strips in position 60 upon the bag comprising opposed fastening mechanisms, one of which is movable upon a common support toward and away from the other of said mechanisms, and means for driving one of said mechanisms from the other, said 65 means allowing movement of the movable mechanism upon said support.

2. In combination; means for positioning a strip of reinforcing material over each corner of an open mouth bag; and means for applying 70 fastening means to retain said strips in position upon the bag comprising opposed fastening mechanisms, one of which is movable upon a common support toward and away from the other of said mechanisms, a drive shaft associated with each fastening mechanism, one of said 75

drive shafts being driven from the other, and a floating shaft through which motion is transmitted from one drive shaft to the other.

3. In a machine for applying fastening means to the corner of a bag, a forked rod, and means 5 to move said rod into position straddling the edge of the bag, the upper fork of said rod being formed to allow fastening means to be driven therethrough, and the lower fork of said rod comprising an anvil against which said fastening 10 means is driven.

4. In a machine for applying fastening means to the corner of a bag, a forked rod, means to move said rod into position straddling the edge of the bag, the upper fork of said rod being slotted 15 to allow fastening means to be driven therethrough, the lower fork of said rod comprising an anvil against which said fastening means is driven, and means to position a strip of reinforcing material between the edge of the bag 20 and the ends of said rod, before movement of said rod past the edge of the bag, to be engaged thereby and folded over the edge of the bag.

5. In a machine for applying fastening means to the corner of a bag, a forked rod, means to move said rod into position straddling the edge of the bag, the upper fork of said rod being slotted 25 to allow fastening means to be driven therethrough, the lower fork of said rod comprising an anvil against which said fastening means is driven, and means comprising a pair of wheels having enlarged portions to position a strip of reinforcing material between the edge of the bag 30 and the ends of said rod, before movement of said rod past the edge of the bag, to be engaged 35 thereby and folded over the edge of the bag.

6. In a machine for applying fastening means to the corner of a bag, a forked rod, means to move said rod into position straddling the edge of the bag, the upper fork of said rod being slotted 40 to allow fastening means to be driven therethrough, the lower fork of said rod comprising an anvil against which said fastening means is driven, means to position the end of a continuous strip of reinforcing material between 45 the edge of the bag and the ends of said rod before movement of said rod past the edge of the bag, and means to sever said end from said strip as said forked rod engages the same to hold it against the bag.

7. In a machine for applying fastening means to the corner of a bag, a forked rod, means to move said rod into position straddling the edge of the bag, the upper fork of said rod being slotted 50 to allow fastening means to be driven therethrough, the lower fork of said rod comprising an anvil against which said fastening means is driven, means comprising a pair of wheels having enlarged portions to position the end of a continuous strip of reinforcing material 55 between the edge of the bag and the end of said rod, and means to sever the end of said strip from the remainder thereof.

8. A machine for applying fastening means to the corners of bags comprising, spaced stapling 60 heads, strip feeding and severing means associated with each stapling head, means to fold a severed piece of reinforcing material around each corner of the bag, and a common drive for all 65 of said means.

9. A machine for applying fastening means to the corners of bags comprising, spaced stapling 70 heads, strip feeding and severing means associated with each stapling head, means to fold a piece of reinforcing material around each corner of the 75

bag, a common drive for all of said means, and a one-revolution clutch associated therewith to allow intermittent operation of said means.

- 5 10. In a machine for applying gusset holding means to the corner of a bag, means to fold the end of a strip of material over the edge of the bag, means to separate the end to be folded from the remainder of said strip, and means to staple said end in folded position to the bag.
- 10 11. In a machine for applying gusset holding

means to the corner of a bag, means to fold the end of a strip of material over the edge of the bag, a shear and mechanism causing said shear to separate said end from the remainder of said strip, and means to drive an element through 5 the folded end and the bag.
